SELF-THREADING NEEDLE

Omer J. Rainville, South Attleboro, Mass., assignor to E. Z. I. Needle Co., Providence, R. I., a corporation of Rhode Island

Application July 27, 1937, Serial No. 156,017

5 Claims. (Cl. 112—224)

This invention relates to certain new and useful improvements in self-threading needles.

The primary object of the invention is to provide a needle of a self-threading character wherein in the needle may be designed for either machine or hand sewing, the pin or shank of the needle having the longitudinal side section thereof cut away and replaced by a resilient arm anchored at one end to the needle shank for restoring the cross-sectional shape of the needle to its original form with the free end of the arm adapted to be moved against the resiliency thereof away from the shank of the needle for the introduction of a thread into the eye portion of the needle shank.

15 A further object of the invention is to provide a self-threading needle of the foregoing character wherein the pin or shank of the needle has a cut-away side portion replaced by a resiliently mounted arm that overlies thread guiding projections carried by the pin or shank with side grooves in the shank through which the thread may be trained, for positioning the thread interiorly of the shank of the needle so that the least resistance is offered to the needle when passing through a piece of fabric or the like.

With the above and other objects in view that will become apparent as the nature of the invention is better understood, the same consists in the novel form, combination and arrangement 30 of parts hereinafter more fully described, shown in the accompanying drawing and claimed.

In the drawing:

Figure 1 is a side elevational view of a hand sewing needle constructed in accordance with the present invention;

Figure 2 is a fragmentary side elevational view of the needle shown in Figure 1, taken from another side thereof;

Figure 3 is an enlarged fragmentary elevational view of the eye end of the needle shown in Figures 1 and 2, with the resilient arm removed to illustrate the overlapping thread guide projections in the eye portion of the needle;

Figure 4 is a cross-sectional view taken on line 4—4 of Figure 1;

Figure 5 is a side elevational view of a sewing machine needle equipped with the self-threading attachment;

Figure 6 is another side elevational view of the form of sewing machine needle shown in Figure 5;

Figure 7 is a fragmentary elevational view of the eye end of the sewing machine needle with the resilient arm removed to illustrate the thread guide projections of the needle eye and illustrat-

ing the overlapping arrangement of the thread guide projections; and

Figure 8 is a fragmentary plan view of another form of needle wherein the thread guide projections in the eye portion thereof are directed towards and terminate in spaced relation to each other.

Referring more in detail to the accompanying drawing and particularly to Figures 1 to 4, there is illustrated a hand sewing needle embodying 10 a pin or shank 10 with the tapered or pointed end 11 and an eye portion 12 at the opposite end equipped or constructed to form the self-threading characteristic.

The eye portion 12 of the needle shank 10 is 15 cut away at one side thereof to provide abutment shoulders 13 and 14, the shoulder 13 extending at right angles to the longitudinal axis of the shank 10 while the shoulder 14 tapers as shown in Figures 1 and 2 for purposes presently 20 to appear. A pair of projections of substantially triangular formation as shown at 15 and 16 rises from the cut-away side portion of the needle, the bases of the projections 15 and 16 respectively extending from the shoulders 13 and 14 and being 25 rectangular triangles with the straight side 17 set inwardly of the opposite sides of the eye portion 12 while the hypotenuse 18 of each projection 15 and 16 extends diagonally of the eye portion 12 in spaced and overlapping relation, 30 the arrangement and configuration of the projections 15 and 16 forming side grooves 19 and a diagonal groove 20 therebetween. A side arm 21 is set into the cut-away portion of the shank 10 to overlie the thread guide projections 15 and 16 with the end 22 of the arm 21 welded or otherwise anchored to the abutment shoulder 13, the arm 21 being resilient and having the other end thereof tapered as at 23 and slightly spaced from the inclined shoulder 14 to provide an entrance 40 for the sewing thread to the eye portion 12 of the needle.

To thread a needle, the thread is inserted between the tapered end 23 of the resilient arm 21 and the inclined shoulder 14 of the cut-away portion of the needle shank, the resiliency of the arm 21 permitting the thread to be moved between the arm and the projections 15 and 16 for entry into the diagonal groove 20, the looped portions of the thread then occupying side grooves 19 so that the least resistance is offered to the needle in passage through a piece of fabric or the like.

In the form of invention shown in Figures 5 to 7, the needle 18a is of the sewing machine type, having a pointed end 11a and a head 16a for 55

mounting in a socket. The shank 10a is longitudinally cut-away at one side thereof substantially from the point 11a to the head 11b providing abutment shoulders 13a and 14a, a resilient arm 21a overlying the cut-away portion and welded or otherwise secured at one end thereof to the abutment shoulder 13a. The cut-out portion of the shank 10a includes a side groove 19a that extends substantially the entire length of the shank between the shoulders 13a and 14a and a second side groove 19b extending a short distance from the abutment 13a along the shank 10a. The cut-away portion of the shank 10a that underlies the resilient arm 21a adjacent the point 11a has triangular projections 15a and 16a rising therefrom, similar to the thread guide projections 15 and 16 as shown in Figure 3, the projections 15a and 16a overlapping each other as shown in Figure 7 to provide a diagonal thread guide channel 20a. A thread is introduced into the guide channel 20a by inserting the same under the bevelled end 23a of the side arm 21a and moving the thread along the needle shank for reception in the diagonal guide 20a, a portion of the thread fed from a spool on the head of the machine is trained through the side groove 19a, while the other end of the thread extending through the diagonal groove 20a is fed by the point 11a to a piece of fabric or other material to be sewed.

In each of the forms of invention described, the thread guide projections overlap each other to provide a diagonal thread guide channel groove, but in Figure 8 which shows a modified construction of the thread guide, the thread guide blocks 15b and 16b that rise from the cut-away portion of the needle shank 10b are of triangular shape with the pointed ends thereof terminating in spaced relation to each other on the longitudinal axis of the needle to provide a transverse thread guide 20b.

As shown in Figures 3, 7 and 8 the pointed ends of the triangular projections 16, 15a and 15b are undercut as at 25 at the points thereof to cause the thread to lie more closely to the body of the needle.

From the above detailed description of the invention, it is believed that the construction and use thereof will at once be apparent and while there are herein shown and described the preferred embodiments of the invention, it is nevertheless to be understood that minor changes may be made therein without departing from the spirit and scope of the invention as claimed.

55. What is claimed is:

1. In a self-threading needle, a needle shank having a cut-away portion at one side, the needle having an eye portion including raised thread guide projections carried by the cut-away por-

tion, said projections being integral with the cut-away portion and having pointed ends disposed inwardly of the opposite sides of the needle shank and overlapping each other to provide a thread guide groove extending at an acute angle to the longitudinal axis of the needle shank and a resilient arm overlying the cut-away portion and raised projections and engaged with said projections.

2. In a self-threading needle, a needle shank 10 having a cut-away portion at one side, the needle having an eye portion including raised thread guide projections carried by and integral with the cut-away portion and a resilient arm overlying the cut-away portion and raised projections, 15 said projections being rectangular triangles with the inclined sides and apices being laterally disposed with the apices overlapping each other and spaced apart to form a diagonal thread guide groove.

3. In a self-threading needle, a needle shank having a cut-away portion at one side, the needle having an eye portion including raised thread guide projections carried by and integral with the cut-away portion, a resilient arm overlying 25 the cut-away portion and raised projections, said projections being rectangular triangles with the inclined sides and apices being laterally disposed with the apices overlapping each other and spaced apart to form a diagonal thread guide groove, 30 and said arm being anchored to the shank at one end.

4. In a self-threading needle, a needle shank having a cut-away portion at one side, the needle having an eye portion including raised thread 35 guide projections carried by and integral with the cut-away portion with adjacent portions of the projections laterally disposed and overlapping each other to provide a thread guide eye extending at an acute angle to the longitudinal 40 axis of the needle and a resilient arm overlying the cut-away portion and raised projections and engaged with said projections, said needle being of the sewing machine type with the thread guide projections adjacent the pointed end thereof. 45

5. In a self-threading needle, a needle shank having a cut-away portion at one side, the needle having an eye portion including raised thread guide projections carried by and integral with the cut-away portion with adjacent portions of the 50 projections laterally disposed and overlapping each other to provide a thread guide eye extending at an acute angle to the longitudinal axis of the needle, a resilient arm overlying the cut-away portion and raised projections and engaged with 55 said projections, and said shank having a thread guide groove extending longitudinally thereof for a portion of its length.

OMER J. RAINVILLE.
